DESIGN FOR A COMBINED COASTER SET AND HOLDER THEREFOR

Achille G. Bureau, Forest Hills, N. Y., assignor to Ranger-Tennere, Inc., New York, N. Y., a corporation of New York

Application January 10, 1946, Serial No. 125,408

Term of patent 7 years

(Cl. D44—7)

To all whom it may concern:

Be it known that I, Achille G. Bureau, a citizen of the United States and a resident of Forest Hills, in the county of Queens and State of New York, whose post-office address is 374 Burns Street, Forest Hills, New York, have invented a new, original, and ornamental Design for a Combined Coaster Set and Holder Therefor, of which the following is a specification, reference being had to the accompanying drawing, forming part thereof.

I claim:

The ornamental design for a combined coaster set and holder therefor, substantially as shown.
